(57) **CLAIM**

The ornamental design for a lighting controller, as shown and described.

DESCRIPTION

FIG. 1 is a bottom, front, and right side perspective view of the design according to the invention wherein a portion is shown in exploded condition for clarity.

FIG. 2 is a top, front, and right side perspective view of the design according to the invention wherein a portion is shown in exploded condition for clarity.

FIG. 3 is a front view of the design according to the invention.

FIG. 4 is a rear view of the design according to the invention.

FIG. 5 is a top view of the design according to the invention.

FIG. 6 is a bottom view of the design according to the invention.

FIG. 7 is a left side view of the design according to the invention.

FIG. 8 is a right side view of the design according to the invention; and,

FIG. 9 is a sectional view of the design according to the invention taken along line 9—9 in FIG. 3.
